CONTROL APPARATUS FOR REVERSIBLE INTERNAL-COMBUSTION ENGINES

Roy R. Stevens, Forest Hills, Pa., assignor to
The Westinghouse Air Brake Company, Wil-
merding, Pa., a corporation of Pennsylvania

Application June 29, 1945, Serial No. 602,255

13 Claims. (Cl. 123—41)

1

This invention relates to control apparatus and more particularly to apparatus arranged to control a plurality of different operations in a desired sequence, such, for example, as operations incident to the control of a reversible prime mover.

One object of the invention is the provision of an improved control apparatus of the above type.

Another object of the invention is the provision of a pneumatic control apparatus of the above type which is particularly adapted, though not limited, to control particularly the speed of or fuel supply to a reversible prime mover from a remote control station.

Other objects and advantages will be apparent from the following more detailed description of the invention.

In the accompanying drawing; Fig. 1 is a diagrammatic view, partly in section and partly in outline, of a control apparatus embodying the invention; and Fig. 2 is a cross-sectional view of a directional control device shown in Fig. 1 inside elevation and taken on the line 2—2 therein.

Description

In the drawing, the reference numeral 1 indicates an engine crank shaft and the reference numeral 2 indicates a cam shaft for said engine. The engine is of the type in which the cam shaft 2 is shiftable longitudinally to different positions which determine the direction of operation of the engine, and the cam shaft may therefore have what may be called an astern position, in which it is shown in the drawing, and may be shiftable from this position in the direction of the right hand to an ahead position. As above used, the term astern indicates operation of the engine in one direction, and the term ahead indicates operation of the engine in the opposite direction, and these terms are merely employed for illustration and are to be considered synonymous with said one and opposite directions.

The reference numeral 3 indicates a fuel control shaft for the engine. The fuel control shaft 3 may have a fuel cut-off position, such as indicated by a dot and dash line 4, and may be rockable out of this position in a counterclockwise direction as viewed in the drawing for increasing the supply of fuel to the engine. A dot and dash line 5 indicates a position which the fuel control shaft 3 may assume to provide a maximum amount of fuel to the engine.

The numeral 6 indicates a maneuvering control shaft for the engine. An operating lever 7 secured to one end of shaft 6 for turning same, is disposed behind an escutcheon plate 8 and is

5 9 operatively connected to an operating knob 9 in front of said plate. The knob 9 is provided for the operator to grasp to operate lever 7 to turn the shaft 6. The lever 7 has a "Stop" position in which it is arranged vertically as shown in the drawing, and is movable from this position either in a counter-clockwise direction toward the legend "Astern" on the plate 8, or in the opposite direction toward the legend "Ahead" on said plate. 10 At the "Astern" side of "Stop" position the lever 7 has "Shift," "Run" and "Start" positions arranged in the order named with the "Shift" position adjacent the "Stop" position, while corresponding but reversely arranged positions are provided at the opposite or "Ahead" side of "Stop" position. Movement of lever 7 to any of these different positions will correspondingly position the maneuvering shaft 6.

15 The reference numeral 11 indicates a reversing motor for moving the engine cam shaft 2 to its different positions, while the reference numeral 12 designates a control valve mechanism arranged for control by the maneuvering shaft 6 for controlling operation of said motor.

20 25 The reversing motor 11 comprises a casing containing a piston 13 having a piston rod 14 extending through the casing in coaxial relation with and having its end connected to the cam shaft 2 whereby reciprocation of said piston will move said cam shaft longitudinally. At one side of piston 13 30 is a pressure chamber 15 connected to a control pipe 16, while at the opposite side of said piston is a pressure chamber 17 connected to a control pipe 18. When fluid under pressure is supplied to pipe 16 at a time when pressure chamber 17 is open 35 to atmosphere by way of pipe 18, piston 13 will be moved to the position in which it is shown in the drawing for moving the cam shaft 2 to its astern position to provide for operation of the engine in the astern direction. On the other hand, when pipe 16 and thereby pressure chamber 15 are open to atmosphere and fluid under pressure is supplied through pipe 18 to pressure chamber 17 the piston 13 will be moved to the opposite or right-hand end of its cylinder to thereby move 40 the cam shaft 2 to its ahead position.

45 The control valve mechanism 12 comprises an astern valve device 20 for controlling the supply and release of fluid under pressure to and from pipe 16 and an ahead valve device 21 for controlling the supply and release of fluid under pressure to and from the pipe 18. The ahead and astern valve devices 20 and 21 are identical in structure, each comprising a supply valve 22 contained in a chamber 23, which chamber is common to the two valves and adapted to be con-

stantly supplied with fluid under pressure from any suitable source by way of a pipe 24. Each of the valves 22 is arranged to control flow of fluid under pressure from chamber 23 to a chamber 25 and is provided with a stem 26 extending through the latter chamber and a bore in the casing into a chamber 27 which is open to atmosphere by way of a port 28. Chamber 25 in the ahead valve device 21 is connected to pipe 18, while said chamber in the astern valve device 20 is connected to pipe 16. Each valve stem 26 is provided with an axial bore 29 open at one end to chamber 25 and open at the opposite end through the end of said stem in chamber 27. A plunger 30 slidably mounted in a bore in the casing, extends into chamber 27 in coaxial relation with the adjacent end of each valve stem 26, and one end of said plunger constitutes a valve arranged to cooperate with a seat on the adjacent end of said stem for closing communication between bore 29 and chamber 27. A spring 33 contained in chamber 23 acts on each supply valve 22 for urging it to its closed position.

Two identical but reversely arranged cams 31 and 32 are mounted on the maneuvering shaft 6 for cooperation with the two plungers 30 to control operation of the ahead and astern valve devices 21 and 20, respectively. With the operator's control lever 7 in the "Astern" "Shift" position the cam 32 is adapted to seat plunger 30 in the astern valve device 20 against the end of the respective supply valve stem 26 and to open said valve for supplying fluid under pressure to pipe 16, while in all other positions of said lever, said cam is adapted to permit closing of said valve by the respective spring 33 and to also permit movement of the respective plunger 30 to the position shown in the drawing for releasing fluid under pressure from chamber 25 and pipe 16 through bore 29 in the respective supply valve stem 26 to chamber 27 and thence to atmosphere. In a like manner the cam 31 is adapted to operate upon movement of the operator's control lever 7 to the "Ahead" "Shift" position to supply fluid under pressure to pipe 18 and in all other positions of said lever to open said pipe to atmosphere.

It will thus be apparent that when the operator's control lever 7 is moved to the "Astern" "Shift" position, the control valve device 12 will operate to supply fluid under pressure to chamber 15 to effect operation of the reversing motor 11 to move the cam shaft 2 to its astern position to provide for operation of the engine in the one direction, but movement beyond this "Shift" position in the direction of and to the "Astern" "Run" and "Start" positions will cause operation of the control valve mechanism 12 to release fluid under pressure from said piston chamber. Likewise, if the operator's control lever is moved to the "Ahead" "Shift" position the control valve mechanism 12 will be operated to supply fluid under pressure to chamber 17 in the reversing motor 11 to effect operation of said motor to move the engine cam shaft to its ahead position, while movement past the "Ahead" "Shift" position will cause operation of said device to release fluid under pressure from chamber 17. It will thus be seen that it is necessary for the operator in reversing the direction of operation of the engine to allow lever 7 to remain in the "Astern" "Shift" position or in the "Ahead" "Shift" position for a period of time sufficient for the reversing motor 11 to properly position the cam shaft 2.

Fluid is released from pressure chamber 15 or 17 in the reversing motor, after it has operated to properly position the cam shaft 2 as above described to remove thrust on the connection between the reversing piston 13 and the cam shaft 2.

The reference numeral 35 indicates an engine starting air valve device which is operative to supply engine starting air from a supply pipe 36 to a pipe 37 which is adapted to conduct such starting air to the starting mechanism of the engine for starting the engine to turn in the direction determined by the position of the cam shaft 2.

The starting air valve device 35 comprises a casing having a chamber 34 connected to the supply pipe 36 and containing a valve 38 arranged to control flow of starting air from said chamber to pipe 37. The valve 38 has a fluted stem 39 engaging a like stem on an oppositely seating valve 40 contained in a chamber 41 which is open to atmosphere through a port 42. The valve 40 is arranged to control communication between pipe 37 and atmospheric port 42. A spring 43 in chamber 34 acts on the supply valve 38 for urging it to its seated position and for unseating the valve 40, while a stem 44, projecting from valve 40 through chamber 41 and a bore in a casing, is provided for closing valve 40 and opening valve 38 against spring 43. A cam 45 secured to the maneuvering shaft 6 for operation thereby is arranged to operate stem 44 to close valve 40 and open valve 38 in the two "Start" positions of the operator's control lever 7 and to permit closure of valve 38 and opening of valve 40 by spring 43, in all other positions of said lever. It will thus be apparent that when the operator's control lever 7 is moved to either of the two "Start" positions, engine starting air will be supplied to pipe 37 to effect starting of the engine, while in all other positions of said lever pipe 37 will be open to atmosphere.

It should here be mentioned that the parts or devices thus far described have heretofore been employed in engine control apparatus and said parts or devices taken separately do not constitute applicant's invention, however, the combination of these parts with other parts and devices, as will now be described, does constitute the present invention.

Associated with the apparatus thus far described is a power means in the form of a fluid motor 47 adapted to be controlled by an operator's control device 48 which may be located at a remote station, if desired, for controlling movement of the maneuvering shaft 6 to its different positions. The power means 47 and operator's control device 48 may be like similar devices fully disclosed in Patent No. 2,383,278, issued to me on August 21, 1945 and since reference may be made thereto the following description of the power means 47 and operator's control device 48 will therefore be limited to only such details as is deemed essential to a clear understanding of the present invention.

Briefly, the power means 47 in the form of a fluid motor, is arranged to be operated by fluid under pressure supplied to either an ahead pipe 50 or to an astern pipe 51 to turn the maneuvering shaft 6 in, respectively, either the "Ahead" direction or the "Astern" direction, through the medium of a sprocket wheel 52 associated with the motor, a sprocket wheel 53 secured to the maneuvering shaft 6 and a connecting chain 54. The

motor 47 is adapted to assume different positions corresponding to different pressures of fluid in either the ahead pipe 50 or the astern pipe 51, so that by providing different selected pressures of fluid in the ahead pipe 50, for instance, the maneuvering shaft 6 can be caused to assume any position at the "Ahead" side of "Stop" position, while the provision of the same selected pressures of fluid in the astern pipe 51 will cause the maneuvering shaft 6 to assume the corresponding positions at the "Astern" side of "Stop" position. When both pipes 50 and 51 are open to atmosphere the motor 47 will operate to move the maneuvering shaft 6 to "Stop" position.

From the above remarks it will be seen that if a certain pressure of fluid in the ahead pipe 50 will cause the maneuvering shaft 6 to assume "Ahead" "Shift" position and a certain greater pressure of fluid will cause said shaft to assume "Ahead" "Run" position, the shaft 6 may be caused to assume any position between said "Shift" and "Run" positions by providing in said pipe fluid at the proper pressure between said certain pressure and said certain greater pressure. Likewise, the maneuvering shaft 6 may be caused to assume any position between "Shift" and "Run" positions at the "Astern" side of "Stop" position by providing fluid at the proper selected pressure in the astern control pipe 51.

The operator's control device 48 comprises a lever 55 having a neutral or "Stop" position and at one or an "Astern" side thereof "Shift," "Run" and "Start" positions, and at the opposite or "Ahead" side of "Stop" position reversely arranged "Shift," "Run" and "Start" positions, these positions corresponding in name and disposition it will be noted, to the different positions of the operator's control lever 7 and maneuvering shaft 6. Between the "Shift" and "Run" positions at both sides of stop position there is a zone of movement designated "Fuel limiting zone" the purpose of which will be hereinafter brought out.

The operator's control device 48 is arranged to control the supply and release of fluid under pressure to and from two pipes 56 and 57 which are adapted to be connected to pipes 50 and 51, respectively, by means to be later described. In "Stop" position of lever 55 the operator's control device 48 is adapted to open both pipes 56 and 57 to atmosphere for thereby releasing fluid from both of the pipes 50 and 51 to cause operation of motor 47 to move the maneuvering shaft 6 and lever 7 to their corresponding or "Stop" position. Movement of the operator's control lever 55 to any of its different positions at the "Ahead" side of "Stop" position is adapted to maintain pipe 57 open to atmosphere and to supply fluid to pipe 56 at a pressure such as required to effect operation of motor 47 to move the maneuvering shaft 6 to the position corresponding to that of said lever. Movement of the operator's control lever 55 to the "Astern" side of "Stop" position will maintain pipe 56 open to atmosphere and supply fluid to pipe 57 at a pressure corresponding to the position of said lever to thereby effect operation of motor 47 to correspondingly position the maneuvering shaft 6. In other words, the motor 47 will act in response to any selected positioning of the operator's control lever 55 to move the fuel control shaft 6 to the corresponding position.

Interposed in the communication between pipes 56 and 50 and pipes 57 and 51 are two pressure limiting valve devices 59 and 60, respectively, and an interlock valve device 61.

Each of the limiting valve devices 59 and 60

comprises a casing having a chamber 62 containing a valve 63 arranged to control flow of fluid under pressure from said chamber to a chamber 64. A spring 65 in chamber 62 acts on valve 63 for urging it toward its seat. The valve 63 has a stem 66 extending into chamber 64 and operatively connected to a flexible diaphragm 67 which forms one side of chamber 64. At the opposite side of diaphragm 67 is a chamber 68 which is open to atmosphere through a passage 69 and which contains a spring 70 acting on the diaphragm in a direction to unseat the valve 63. The pressure of spring 70 on diaphragm 67 is such as to permit deflection of said diaphragm and closing of valve 63 by spring 65 when the pressure of fluid in chamber 64 is increased to a certain chosen degree, for reasons which will be later brought out. In the pressure limiting valve device 59 chamber 62 is connected to pipe 56 while chamber 64 is connected to pipe 50, while in the limiting valve device 60 said chambers are connected respectively to pipes 57 and 51.

The pipes 56, 57, 50 and 51 all lead to the interlock valve device 61 which may comprise a rotary valve 72 having two different operating positions and which is arranged to be moved to said positions by a lever 73. The lever 73 is operatively connected to a rod 14 which has a lost motion connection with a rod 75 through the medium of an arm 76 on rod 75 and spaced collars 77, 78 on rod 14. The rod 75 is connected to the reversing piston 13 at the side opposite the piston rod 14.

When the reversing piston 13 is in its astern position, in which it is shown in the drawing, engagement between arm 76 on rod 75 and collar 77 on rod 14 will position the rotary valve 72 in the interlock valve device in what may be called an astern position in which it also is shown in the drawing. When, however, the reversing piston 13 is moved to its ahead position at the opposite or right hand end of the cylinder, the arm 76 will engage collar 78 on rod 14 just before the piston attains said position in order to actuate lever 73 to turn rotary valve 72 to its other position, which may be called an ahead position, and in which said lever will occupy a position such as indicated by a line 79. It will be apparent that movement of piston 13 from its ahead position to its astern position, in which it is shown in the drawing, will return the rotary valve 72 to the position in which it is shown in the drawing.

The rotary valve 72 is provided with two cavities 80 and 81, the cavity 80 being adapted to establish communication between pipes 57 and 51 in the astern position of said valve, while the cavity 81 is adapted to establish communication between pipes 56 and 50 in the ahead position of said valve. When communication is established between pipes 57 and 51, the communication between pipes 56 and 50 will be broken, and vice versa.

Connected to one end of the fuel control shaft 3 is a lever 82 having in its free end a roller 83 engaging the peripheral surface of a cam 84 which is secured to the maneuvering shaft 6 for adjustment thereby. When the maneuvering shaft 6 is in "Stop" position cam 84 is adapted to actuate lever 82 to move the fuel control shaft 3 to its fuel cut-off position, indicated by the dot and dash line 4. Movement of the maneuvering shaft 6 from "Shift" position to "Run" position at each side of "Stop" position is adapted to actuate cam 84 to permit movement, by means to be hereinafter described, of lever 82 and thereby of

7

the fuel control shaft 3 in a counterclockwise direction a degree proportional to the extent of such movement. In both "Run" positions of shaft 6 and cam 84 the fuel control shaft 3 will be permitted to move to the maximum fuel supply position indicated by the dot and dash line 5. It will thus be seen that the supply of fuel to the engine may be graduated from no fuel to a maximum degree by proper adjustment of the maneuvering shaft 6 in the "Fuel limiting zone" between "Shift" position and the adjacent "Run" position at either side of "Stop" position, and it therefore follows that, since the power motor 47 will position the maneuvering shaft 6 in accordance with the position of the operator's control lever 55, movement of lever 55 to "Stop" position will cause operation of cam 84 to cut off the supply of fuel to the engine, while suitable adjustment of said lever between the "Shift" and "Run" positions at either side of "Stop" position will correspondingly position cam 84 to limit movement of the fuel control shaft 3 out of its fuel cut-off position, to in turn limit the degree of fuel supplied to the engine to an amount corresponding to the position of lever 55.

Also operatively connected to the fuel control shaft 3 is one end of an arm 86 the opposite end of which is connected by a link 87 to one end of a lever 88. The lever 88 is pivoted intermediate its ends on a fixed fulcrum pin 89 and the opposite end of said lever is operatively connected to a plunger 90 of a speed governor 97.

The speed governor 97 comprises a head 91 in which the opposite end of plunger 90 is slidably mounted. Two centrifugal governor arms 92 are pivoted on pins 93 in head 91 and are operatively connected to a collar 94 secured to plunger 90. The head 91 is operatively connected by gears 95, 96 to any suitable rotatable part of the engine, such as the crank shaft 1. Upon an increase in speed of the crank shaft 1 the governor arms 92 will act through plunger 90, lever 88, and arm 86 to move the fuel control shaft 3 in the direction of the fuel cut-off position indicated by the dot and dash line 4, while movement of said lever in the opposite direction against the opposing action of the governor arms 92 will actuate arm 86 to move the fuel control shaft 3 in the opposite direction or out of the fuel cut-off position.

The governor 97 further comprises a control spring 98, having one end connected to lever 88 between the fulcrum pin 89 and the link 87, to oppose the action of centrifugal force on the governor arms 92. The opposite end of spring 98 is connected to one end of a rod 99 of a fuel control motor 100 which is operative to adjust the pressure or force of said spring on said lever. The motor 100 may be like the motor disclosed in the copending application of Myself et al., Serial No. 569,545, filed December 23, 1944 now Patent No. 2,444,244, and assigned to the assignee of the present application, but is shown in the drawing of the present application, for the purpose of illustration only, as comprising a cylinder 101 containing a piston 102 to which the rod 99 is operatively connected. At one side of piston 102 is a control chamber 103 connected to a control pipe 104, while at the opposite side of said piston is a non-pressure chamber 105 which is open to atmosphere through a passage 106 and which contains a control spring 107 acting on the piston 102 in opposition to pressure of fluid in chamber 103.

The pipe 104 leads to an operator's fuel or speed control device 108 located adjacent the maneuver-

ing control device 10. The speed control device 108 may be of any suitable type which will vary the pressure of fluid in pipe 104 in proportion to movement of a control lever 109 out of a position in which said pipe will be open to atmosphere. This position of lever 109 is designated in the drawing by the legend "Idle." A maximum pressure of fluid will be obtained in pipe 104 with lever 109 moved to a position designated in the drawing by the legend "Full speed." Devices of this type are so well known that no further description thereof is deemed necessary in the present application, but reference may be made, if desired, to Patent No. 2,329,742 issued to Franklin J. Bush et al. on September 21, 1943 which discloses a device of this general type.

The reference numeral 110 indicates a fuel cut-off motor which is arranged beside the governor control motor 100. The cut-off motor 110 comprises a casing containing a piston 111 which is provided with a rod 112 extending through a non-pressure chamber 113 at one side of the piston for engagement with arm 86 which is secured to the fuel control shaft 3. The non-pressure chamber 113 contains a spring 114 acting on piston 111 for moving the rod 112 in a direction away from the fuel control arm 86. At the opposite side of piston 111 is a pressure chamber 115 which is connected to a control pipe 116. With chamber 115 vented by way of pipe 116 the piston 111 will assume the position shown in the drawing under the pressure of spring 114 to thereby withdraw rod 112 to a position which will permit movement of the fuel control arm 86 and fuel control shaft 3 to their maximum fuel supply position indicated by the dot and dash line 5. Movement of piston 111 and rod 112 in the opposite direction against spring 114 is adapted to be limited by engagement of said piston with a shoulder 117 in the casing. With the piston 111 in contact with shoulder 117 the rod 112 will be positioned to hold the arm 86 and thereby the fuel control shaft 3 in the fuel cut-off position indicated by the dot and dash line 4.

The fuel cut-off control pipe 116 leads to a directional control device 118 which is arranged to control communication between said pipe and the ahead and astern pipes 50 and 51.

The directional control device 118, constituting an improvement over that disclosed in my Patent 2,413,390, issued December 31, 1946, and covered, per se, in the copending application of Cecil S. Kelley, Serial No. 625,011, filed October 27, 1945, now Patent No. 2,459,883, and assigned to the assignee of the present application comprises (Fig. 2) two poppet valves 119 and 120 contained in chambers 121 and 122 which are open to the ahead and astern pipes 50 and 51, respectively. The two valves 119 and 120 are arranged side by side with parallel extending fluted stems 123 and 124, respectively, which extend into a chamber 125 to which is connected pipe 116. The valves 119 and 120 are provided to control communication between chambers 121 and 122, respectively, and chamber 125 as will be apparent, and a spring 126 provided in each of the chambers 121 and 122 acts on the respective valve 119 and 120 to urge it to its closed position.

The valve stems 123 and 124 engage respectively two spaced and coaxially arranged operating plungers 127 and 128 which are slidably mounted in the casing and which are provided with stems 129 and 130 extending to the exterior of the casing through sealing rings 131 which are adapted to prevent leakage of fluid under pres-

sure from chamber 125 past the respective plungers and stems to atmosphere. Two rockable cams 132 and 133 fulcrumed on pins 134 in the casing are provided for controlling the plungers 129 and 130, respectively. These cams are of substantially identical structure but reversely arranged and each is connected to the respective plunger 129 or 130 through the medium of a pressure transmitting element 135 which is rockably mounted on a pin 136 carried in the casing. Each of the cams 132 and 133 is provided with a surface 137 which when in contact with plunger 129 or 130 will unseat the respective valve 119 or 120, and adjacent this surface each cam is provided with a recess 138 adapted to receive the respective element 135 to permit movement of the respective plunger 127 or 128 by a spring 139 to a position to permit closure of the respective valve 119 or 120 by spring 126. The two cams 132 and 133 are operatively connected for movement in unison by a link 140 and since the cams are reversed, as above mentioned, movement of the link and thereby of the cams to the position in which they are shown in the drawing will effect opening of valve 119 and closure of valve 120, while movement of said link and cams in a counter-clockwise direction, as viewed in the drawing, to a position in which surface 137 on cam 133 engages the respective element 135, will effect opening of valve 120 and closure of valve 119.

The directional control device 118 further comprises a control piston 142 and a piston rod 143 having one end connected to said piston and extending through a non-pressure chamber 144 at one side of said piston. At the opposite side of piston 142 is a pressure chamber 145 which is in constant communication through a pipe 146 with pipe 37 through which starting air is conveyed to the engine.

The opposite end of the piston rod 143 is pivotally connected by a pin 147 to a lug 148 projecting from the back face of a friction shoe 149. The opposite face of shoe 149 is concave providing a surface 150 which is arranged to frictionally engage the peripheral surface of the crank shaft 1. Also connected to pin 147 is one end of a link 151 the opposite end of which is operatively connected to the adjacent end of the cam operating link 140.

The piston rod 143 is capable of side movement in the non-pressure chamber 144 from the position in which it is shown in the drawing, and which is defined by contact with a surface 152 of the casing, to a position in which said rod will engage a surface 153 in the casing. Adjacent the surface 153 the casing is provided underneath the link 150 with a pin 154, and said link has two recesses 155 one of which is arranged to receive the pin 154 with the piston rod 143 in the position in which it is shown in the drawing, while the other recess 155 is disposed to receive pin 154 in the other position of said rod.

The piston rod 143 is encircled within the non-pressure chamber 144 by a spring 156 one end of which engages the piston 142 while the opposite end is supported on a shoulder 157. This spring is under pressure and adapted to act to move the piston 142 to the position in which it is shown in the drawing when pressure chamber 145 is open to the atmosphere. When fluid under pressure is supplied to pressure chamber 145, in a manner which will be later described, the piston 142 is adapted to move against spring 156 to thereby operate rod 143 to move the friction shoe 149 into contact with the crank shaft 1. With

the shoe 149 in contact with the crank shaft the link 151 will be elevated from the position in which it is shown in the drawing and thus disconnected from the pin 155. When fluid under pressure is released from chamber 145, spring 156 is adapted to actuate piston 142 and rod 143 to move the shoe 149 out of contact with the crank shaft and into contact with supporting surfaces 158 on the casing.

Operation

Let it be initially assumed that all parts of the control apparatus are in the position shown in the drawing, which position will result from stopping the engine from operation in an astern direction, as will become apparent from description to follow.

Let it further be assumed that by operation of the maneuvering control device 48 the operator desires to restart the engine in its last direction of operation, that is, in the astern direction in the present instance. To accomplish this the operator will move lever 55 of the maneuvering control valve device 48 out of "Stop" position to the "Astern" "Start" position to thereby supply fluid under pressure to the astern pipe 57. With the cam shaft reversing piston 13 and interlock valve device 61 in their astern position as shown in the drawing, fluid under pressure supplied to pipe 57 will flow through cavity 80 in rotary valve 72 to pipe 51 and thence to power means 47 and effect operation thereof to turn the maneuvering shaft 6 from its "Stop" position to its "Astern" "Start" position.

Upon movement of the maneuvering shaft 6 to its "Astern" "Start" position cam 84 will permit the governor control spring 98 acting through lever 88 to move the fuel control shaft 3 out of its fuel cut-off position indicated by the dot and dash line 4 to a position to provide fuel to the engine for effecting starting thereof. Movement of the maneuvering shaft 6 to its "Astern" "Start" position will also actuate the astern valve device 20 in the control valve mechanism 12 to supply fluid under pressure to chamber 15 in the reversing motor 11, but such fluid in said chamber will be without effect since piston 13 will already be in its astern position. The starting air valve device 35 will also be actuated upon movement of the maneuvering shaft 6 to its "Astern" "Start" position to supply engine starting air from pipe 36 to pipe 37 through which it will be conveyed to the engine to initiate, in a well known manner, turning of the engine in the astern direction as determined by the position of the cam shaft 2.

With fuel supplied to the engine as above mentioned the engine will fire after it is placed in motion by starting air supplied to pipe 37 as just described, following which the operator will move the control lever 55 from the "Astern" "Start" position to the adjacent "Run" position, or to any selected position intermediate said "Run" position and the adjacent "Shift" position, to thereby reduce the pressure of fluid in pipe 57 so that the motor 47 will operate to move the maneuvering shaft 6 out of its "Astern" "Start" position to a position corresponding to the position of lever 55. When the shaft 6 is thus moved out of the "Astern" "Start" position the starting valve device 35 will operate to cut off the supply of starting air through pipe 37 to the engine and to open said pipe to atmosphere. The engine will then continue to run on fuel at a speed determined by the adjustment of lever 109 of the speed control device 108 and thus the adjustment of the governor

motor 100 as limited by adjustment of the maneuvering control lever 55 in or between the "Astern" "Shift" and "Run" positions, as will now be described.

Assuming that lever 109 of the speed control device 108 is allowed to remain in "Idle" position while starting the engine, the parts of the governor control motor 100 will also remain in the position in which they are shown in the drawing. Just as soon as the engine starts to run on fuel the speed governor 97 will then act to rock lever 88 against spring 98 and thus pull the fuel control shaft 3 in a clockwise direction to reduce the amount of fuel supplied to the engine and this action will continue until a balance is obtained between the centrifugal force of the governor arms 92 and the pressure of spring 98 at which time the supply of fuel to the engine will be such as to allow operation of the engine at idling speed.

At the same time or prior to actuating the maneuvering control device 48 to start the engine, the operator may however actuate the speed control device 108 to supply fluid to pipe 104 at a pressure required to cause operation of the engine at a speed in excess of idling speed, in which case, the governor control motor 100 will operate to correspondingly adjust the pressure of the governor control spring 98. Then as soon as the engine starts, the speed governor 97 will become operative to cause the engine to operate at the speed predetermined by the adjustment of the operator's speed control lever 109.

After the engine has been started and is operating on fuel as above described, if the operator desires to increase the speed of the engine, he will move lever 109 away from its "Idle" position to thereby increase the pressure in pipe 104 to a degree corresponding to the position of said lever. This pressure in pipe 104 effective in chamber 103 of the governor control motor 100 will move piston 102 to a position in which the pressure of spring 107 balances the pressure of fluid in chamber 103, and this movement of said piston will act to correspondingly increase the force of the governor control spring 98 against lever 88. The lever 88 will thereby be operated to turn the fuel control shaft 3 in the direction of the maximum fuel position indicated by the dot and dash line 5 to increase the supply of fuel to the engine. The engine will then accelerate and cause operation of the speed governor 97 to rock lever 88 against spring 98 and thus move the fuel control shaft 3 in the opposite direction to reduce the supply of fuel to the engine, and this action will continue until a balance is obtained between the centrifugal force of the governor arms 92 and the adjusted pressure of spring 98, whereby the fuel supply to and thus the speed of the engine will be increased to a degree corresponding to the increase in pressure of fluid in the control pipe 104.

On the other hand, if the engine is operating at a certain speed and the operator desires to reduce the speed he will move lever 109 in the direction of "Idle" position to thereby reduce the pressure of fluid in the control pipe 104 to allow operation of the motor piston 102 by spring 107 to correspondingly reduce the pressure of the governor control spring 98. The speed governor 97 will then act to correspondingly reduce the fuel supply to the engine, so that the engine will decelerate to a speed corresponding to the change in position of the operator's control lever 109. It will thus be seen that by suitable adjustment of the lever 109 any desired rate of fuel supply to and thus speed of the engine may be obtained.

The lever 82, it will be noted, moves with the fuel control shaft 3 when said shaft is adjusted in response to operation of the motor 40 and speed governor 97. With the maneuvering shaft 6 in "Astern" "Run" position the cam 84 will be so disposed as to permit such movement of lever 82 as to permit the fuel control shaft 3 to be turned to its maximum fuel supply position indicated by the dot and dash line 5. However, with the maneuvering shaft 6 adjusted out of the "Astern" "Run" position in the direction of the respective "Shift" position the cam 84 will act to limit movement of lever 82 and thereby of the fuel control shaft 3 to a position proportional to the distance which the maneuvering control shaft 6 is moved out of the "Astern" "Shift" position in the direction of the "Astern" "Run" position. In the "Astern" "Shift" position of the maneuvering shaft 6 the cam 84 will be so positioned as to limit movement of the fuel control shaft 3 out of the fuel cut-off position, indicated by the dot and dash line 4, only to an extent which will permit a supply of fuel to allow operation of the engine at idling speed.

It will now be seen that while the speed of the engine may be regulated by operation of the speed control device 108, the maximum engine speed is limited by the position of cam 84 which in turn is regulated in accordance with the adjustment of the maneuvering shaft 6 and thus the position of the control lever 55 in the maneuvering control valve device 48 in or between the "Shift" and the adjacent "Run" positions at the "Astern" side of "Stop" position. The purpose of thus limiting the amount of fuel that can be supplied to the engine to a maximum degree selected by adjustment of the maneuvering control lever 55 and independent of operation of the speed control device 108 is to prevent accidental undue straining of the engine due to action of the governor to maintain engine speed in case of sudden application of an excessive or abnormal load to the engine.

When the maneuvering shaft 6 is turned to its "Astern" "Start" position, as above described, fluid supplied to the starting pipe 37 will also flow through pipe 146 to pressure chamber 145 in the directional control device 118. The pressure of fluid thus provided in piston chamber 145 will actuate piston 142 and thereby rod 143 to move the shoe 149 into frictional contact with the crank shaft 1. As viewed in Fig. 2 of the drawing, the crank shaft 1 will turn in a clockwise direction upon starting of the engine in the astern direction, so that with shoe 149 in contact with said shaft the piston rod 143 will merely be maintained in contact with surface 152 in the casing of the device. Upon subsequent release of fluid under pressure from the starting air pipe 37 and thus from pipe 146 and piston chamber 145 in the directional control device 118 spring 155 will move the piston 142 back to the position in which it is shown in the drawing for thereby pulling the shoe 149 out of contact with the crank shaft 1.

It will thus be seen that in restarting the engine in the astern direction the parts of the directional control device 118 will not change position. In restarting the engine in the astern direction the valve 120 in the directional control valve device 118 will therefore remain closed so that fluid supplied to the astern control pipe 51 and thence to chamber 122 containing said valve will be prevented from flowing past said valve. The directional control device 118 is there-

fore without utility insofar as restarting the engine in its last direction of operation is concerned, but it is very essential in reversing the direction of operation of the engine as will hereinafter be clearly brought out.

In order to stop the engine from operation in the astern direction the operator need only move lever 55 of the maneuvering control valve device 48 to "Stop" position for opening to atmosphere the astern control pipe 57 and thereby pipe 51 leading to power means 47. The power means 47 will then move the maneuvering shaft 6 to its "Stop" position to thereby effect operation of cam 84 to actuate lever 82 to move the fuel control shaft 3 to the fuel cut-off position indicated by the dot and dash line 4. With the supply of fuel to the engine thus cut off the engine will stop.

With the engine stopped as just described let it be assumed that the operator now desires to start and operate the engine in the ahead direction.

To accomplish this the operator will move lever 55 of the maneuvering control valve device 48 from "Stop" position directly to the "Ahead" "Start" position in which the astern pipe 57 is maintained open to atmosphere and fluid is supplied to the ahead pipe 56 at the maximum pressure required for operating the power means 47 to move the maneuvering shaft 6 to its "Ahead" "Start" position.

Fluid under pressure supplied to pipe 56 as just described will flow through the pressure limiting valve device 59 to pipe 50 and the power means 47, it being noted that communication between the pipes 56 and 50 by way of cavity 81 in the interlock valve 72 is at this time closed, until the pressure acting on diaphragm 67 in said device is increased sufficiently to overcome the opposing force of spring 70 whereupon said diaphragm will move against said spring to permit closure of valve 63 to thereby limit the pressure of fluid in the ahead pipe 50 and in said power means to the chosen degree above mentioned. This chosen degree of pressure provided through pipe 50 in the power means 47 is just sufficient to effect operation of said power means to move the maneuvering shaft 6 to the "Ahead" "Shift" position.

When the maneuvering shaft 6 is turned to the "Ahead" "Shift" position as just described it will operate cam 31 to actuate the ahead valve device 21 in the control valve mechanism 12 to supply fluid under pressure to pipe 18 while allowing the astern valve device 20 to maintain pipe 16 open to atmosphere. With chamber 15 at one side of the cam shaft reversing piston 13 thus open to atmosphere, the pressure of fluid provided through pipe 18 to chamber 17 at the opposite side will move said piston to the opposite or right-hand end of its cylinder for thereby moving the cam shaft 2 from its astern position in which it is shown in the drawing to its ahead position for conditioning the engine for operation in the ahead direction.

When piston 13 is operated to move the cam shaft 2 to its ahead position as just described, the interlock valve device 61 will be operated by said piston by the time said piston has obtained its ahead position to position the valve 72 so as to establish the communication between pipes 56 and 50 by way of cavity 81 in said valve, this communication by-passing the pressure limiting valve device 59. Fluid at the pressure provided in pipe 56 with the operator's control lever 55 in the "Ahead" "Start" position will then become

effective in pipe 50 and in the power means 47 whereupon said power means will operate to turn the maneuvering shaft 6 to the "Ahead" "Start" position.

When the maneuvering control shaft 6 is moved to the "Ahead" "Start" position the cam 31 will operate to effect operation of the ahead valve device 21 to open chamber 17 in the reversing motor 11 to atmosphere for thereby relieving piston 13 and the cam shaft 2 of actuating force, and at the same time this operation of the maneuvering shaft 6 will effect operation of the starting air valve device 35 to supply starting air to pipe 37 for starting the engine to turn in the ahead direction, as determined by the new or ahead position of the cam shaft 2.

Movement of the maneuvering shaft 6 to the "Ahead" "Start" position as just described, will correspondingly position cam 84, but lever 82 and the fuel shaft 3 will remain in the fuel cut-off position, indicated by the dot and dash line 4, at this time for the following reason. Fluid supplied to the ahead control pipe 50 for effecting operation of power means 47 will also flow to valve chamber 121 in the directional control valve device 118 and with valve 119 open at this time, for reasons above described, such fluid will flow past said valve to chamber 125 and thence to pipe 116 leading to chamber 115 in the fuel cut-off motor 110. The fluid pressure thus provided in chamber 115 will move piston 111 to the position defined by contact with stop 117 and in this position of said piston the rod 112 will engage the arm 86 and hold the fuel control shaft 3 in its fuel cut-off position in which it is shown in the drawing.

When fluid under pressure is supplied to pipe 37 to initiate turning of the engine in the ahead direction as determined by the position of cam shaft 2, fluid will also flow from said pipe through pipe 146 to piston chamber 145 in the directional control device 118 and actuate piston 145 against spring 156 to move the friction shoe 149 into contact with the engine crank shaft 1 and to disengage the link 151 from pin 154. As soon as the engine crank shaft 1 starts to turn in the ahead direction under the influence of starting air provided through pipe 37, said crank shaft will move shoe 149 from the position in which it is shown in Fig. 2 of the drawing to the position defined by contact between rod 143 and surface 153 in the casing of the directional control device. This movement of shoe 149 will actuate the links 151 and 140 to rock the cams 132 and 133 to the position to effect opening of valve 120 and to permit closing of valve 119 by spring 126. The closing of valve 119 will cut off the supply of fluid under pressure from the ahead control pipe 50 to chamber 125 in the fuel cut-off motor 110 while opening of valve 120 will connect said chamber to the astern control pipe 51 which is open to atmosphere through the pressure limiting valve device 60 and the maneuvering control valve device 48 with the operating handle 55 thereof in the "Ahead" "Start" position. Fluid under pressure will therefore be released from chamber 115 in the fuel cut-off motor 110 promptly upon the engine crank shaft 1 starting to turn in the direction determined by the cam shaft 2 under the influence of starting air supplied through pipe 37, whereupon spring 114 will move piston 111 and rod 112 in the fuel cut-off motor 110 to the position in which they are shown in the drawing. This movement of rod 112 away from arm 86 on the fuel control shaft 3 will then

permit adjustment of said arm by the governor control spring 98 to a position to supply fuel for starting the engine. With the engine turning under the influence of starting air supplied through pipe 37 the engine will then fire and run on fuel.

After the engine fires and starts to run on fuel the operator will move the control lever 55 of the maneuvering control valve device 48 out of the "Ahead" "Start" position to the adjacent "Run" position or to any desired position intermediate said "Run" position and the adjacent "Shift" position, and this operation of lever 55 will cause operation of power means 47 to correspondingly position the maneuvering shaft 6. The starting air valve device 35 will be operated, in response to this change in position of the maneuvering shaft 6, to release fluid under pressure from the starting control pipe 37 and thereby from pipe 146 and chamber 145 in the directional control valve device 118. Spring 155 acting on piston 142 will then pull the friction shoe 149 out of frictional contact with the revolving crank shaft 1 and during such movement the left hand one of the two recesses 155 in link 151 will move over the pin 154.

With the engine now running on fuel in the ahead direction and the supply of starting air cut off, the operator by suitable adjustment of lever 109 of the fuel control device 108 may regulate the position of the fuel control shaft 3 to obtain any desired engine speed under the control of the speed governor 97 up to the limit permitted by the position of the lever 55 in the maneuvering control valve device 48 in or between the "Ahead" "Run" and the adjacent "Shift" position, as above described.

In order to stop the engine from operation in the ahead direction the operator need only move lever 55 of the maneuvering control valve device 48 to "Stop" position for thereby releasing the fluid under pressure from the ahead control pipe 56 and from pipe 50 leading to power means 47. The power means 47 will then operate to return the maneuvering shaft 6 to its "Stop" position which will actuate cam 84 and thereby lever 82 to move the fuel control shaft 3 to its fuel cut-off position indicated by the dot and dash line 4. With the supply of fuel to the engine thus cut off the engine will stop.

Let it now be assumed that the engine is operating in the ahead direction as just described and that the operator desires to reverse the direction of operation of the engine in as short a time as possible. To accomplish this the operator will move lever 55 in the maneuvering control valve device 48 from whatever position it may be occupying in or between the "Run" and "Shift" positions at the "Ahead" side of "Stop" position to the "Start" position at the opposite or "A stern" side of "Stop" position. Due to this operation of the maneuvering control valve device 48 the ahead control pipe 56 and thereby pipe 50 leading to power means 47 will be opened to atmosphere while fluid at the maximum pressure will be provided in the astern pipe 57. At this time the cam shaft reversing piston 13 will be in its right-hand or ahead position and the interlock valve device 61 will be positioned to close communication between pipes 57 and 51, so that fluid supplied to pipe 57 as just described will flow through the pressure limiting valve device 60 to pipe 51 and thence to the power means 47 and to the directional control device 118 until the pressure of fluid obtained in pipe 51 is increased to that at

which valve 63 in said valve device is closed.

The pressure of fluid thus provided through pipe 51 to the directional control device 118 will then become effective past the open valve 120 therein and through pipe 116 in chamber 115 in the fuel cut-off motor 110 to actuate said motor to rock the fuel control shaft 3 to its fuel cut-off position so as to cut off the supply of fuel to the engine so that the engine may stop. At the same time, the pressure of fluid provided through pipe 51 to power means 47 will actuate said power means to move the maneuvering shaft 6 from the "Ahead" side of "Stop" position to but not past "Shift" position at the opposite or "A stern" side of "Stop" position.

This operation of the maneuvering shaft 6 to the "A stern" "Shift" position will effect operation of the astern valve device 20 in the control valve mechanism 12 to supply fluid under pressure to pipe 16 and chamber 15 at the right-hand side of the cam shaft reversing piston 13. Chamber 17 at the opposite side of the reversing piston 13 is at this time open to atmosphere through pipe 18 and the ahead valve device 21 in the control valve mechanism 12, so that the pressure of fluid provided in chamber 15 will move the piston 13 and thereby the cam shaft 2 from their ahead position to their astern position, in which they are shown in the drawing, to provide for operation of the engine in the astern direction.

Movement of the cam shaft reversing piston 13 to its astern position will turn valve 12 in the interlock valve device 61 back to the position in which it is shown in the drawing to thereby establish communication between pipes 57 and 51 whereby the maximum pressure of fluid provided in the former pipe with the operator's control lever 55 in the "A stern" "Start" position will become effective through pipe 51 in power means 47. The power means 47 will then operate to turn the maneuvering shaft 6 to the corresponding or "A stern" "Start" position for thereby effecting operation of the air starting valve device 35 to supply starting air to pipe 37.

The engine cam shaft 2 may be shifted to its astern position and the starting air valve device 35 may operate to supply engine starting air to pipe 37 as just described before the engine becomes stopped from operation in the ahead direction in which case the starting air supplied to pipe 37 will be effective in the engine to oppose movement of the engine pistons, as well known. After the engine stops however the starting air supplied to the engine through pipe 37 will cause the engine to start turning in the new or astern direction as determined by the position of the reversed cam shaft 2.

Starting air supplied to pipe 37 will also flow through pipe 146 to piston chamber 145 in the directional control valve device and therein act to actuate piston 142 and rod 143 to move the friction shoe 149 into frictional contact with the engine crank shaft 1. If the engine is still operating in the ahead direction at the time the shoe 149 is moved into frictional contact with the engine crank shaft 1, said crank shaft will maintain said shoe and thereby the links 151 and 140 and cams 133 and 132 in the position defined by contact between rod 143 and surface 153 in the casing, so that valve 120 will be maintained open to supply fluid under pressure to the fuel cut-off motor 110 so that said motor will maintain the supply of fuel to the engine cut-off. However, immediately after the engine comes to a stop and then starts to turn in the new or

astern direction under the influence of starting air the clockwise rotation of the engine crank-shaft 1, as viewed in Fig. 2 of the drawing, will move the friction shoe 149 back to the position in which it is shown in the drawing. This movement of shoe 149 will change the position of cams 133 and 132 to permit closure of valve 120 and opening of valve 119. The closing of valve 120 will cut-off the supply of fluid from the astern control pipe 51 to pipe 116 leading to chamber 115 in the fuel cut-off motor 110, and the opening of valve 119 will open said chamber to the ahead control pipe 50 which at this time is open to atmosphere through the operator's maneuvering control valve device 48. Fluid under pressure will thus be released from chamber 115 in the fuel cut-off motor 110 and the rod 112 will be moved by spring 114 away from the arm 86 connected to the fuel control shaft, so that the pressure of the governor control spring 98 on the lever 88 may rock the fuel control shaft 3 out of its fuel cut-off position indicated by the dot and dash line 4 in order to supply fuel to the engine. As soon as the engine fires in response to the fuel thus supplied, the operator will move lever 55 of the maneuvering control valve device 48 from the "Astern" "Start" position either to or to any desired position between the adjacent "Run" and "Shift" positions and then by suitable adjustment of lever 109 of the fuel control device 108 will cause operation of the engine at any desired speed under the control of the speed governor 97, as hereinbefore described.

When the engine is operating in the astern direction if the operator desires to suddenly reverse its direction of operation to ahead, he will move the maneuvering control lever from the "Astern" side of "Stop" position to "Start" position at the "Ahead" side of "Stop" position to thereby open the astern control pipe 51 to atmosphere and to supply fluid at the maximum pressure above mentioned to the ahead control pipe 50. Fluid will then flow from the ahead control pipe 50 through the pressure limiting valve device 59 to pipe 50 leading to the power means 47 and to the directional control device 118 until the pressure in pipe 50 is increased to the chosen degree above-mentioned at which time said limiting valve device will operate to prevent further flow of fluid under pressure to pipe 50.

Fluid under pressure supplied to pipe 50 as just described will flow past the open valve 119 in the directional control device 118 to pipe 116 and thence to the fuel cut-off motor 110 to actuate said motor to cut off the supply of fuel to the engine so that it may come to a stop. At the same time power means 47 will operate in response to the chosen pressure of fluid provided in pipe 50 to turn the maneuvering shaft 6 to the "Ahead" "Shift" position to open valve 22 in the ahead valve 21 of the control valve device 12 so as to supply fluid under pressure to chamber 17 in the cam shaft reversing motor 11. The reversing piston 13 will then operate to move the cam shaft 2 to its right hand or ahead position and to also turn the rotary valve 12 in the interlock valve device 61 to the position to establish communication between pipes 55 and 56. The maximum pressure of fluid provided in pipe 56 will then become effective through pipe 50 in power means 47 and effect operation thereof to turn the maneuvering shaft 6 to its "Ahead" "Start" position.

This movement of the maneuvering shaft 6 to the "Ahead" "Start" position will effect opera-

tion of the ahead valve device 21 to release fluid under pressure from chamber 17 in the cam shaft reversing motor 11, and will also actuate cam 45 to operate the starting air valve device to supply engine starting air to pipe 37. If the engine is still turning in the astern direction the starting air supplied to pipe 37 will be effective to bring the engine to a stop. After the engine is stopped, the starting air supplied to pipe 37 will cause it to start turning in the new or ahead direction corresponding to the position of the cam shaft 2.

Starting air supplied to pipe 37 will also flow through pipe 146 to piston chamber 145 in the directional control device 118 and actuate piston 142 to move the shoe 149 into contact with the crank shaft 2. If the crank shaft 2 is still turning in the astern direction, the shoe 149 will remain in the position shown in the drawing to hold valve 119 open so as to maintain the supply of fluid to the fuel cut-off motor 110 so that said motor will maintain the supply of fuel to the engine cut off. However as soon as the engine crank shaft 2 starts to turn in the ahead direction under the influence of starting air, the shoe 149 will move with said crankshaft to the position defined by contact between rod 143 and surface 153. This movement of shoe 149 will in turn permit closure of valve 119 and effect opening of valve 120 to thereby cut off the supply of fluid under pressure to and to release the fluid under pressure from chamber 115 in the fuel cut-off motor 110. Rod 112 in the fuel cut-off motor 110 will then be moved by spring 114 away from lever 86 to permit operation of the fuel control shaft 3 by the governor control spring 98 to supply fuel to the engine. With the engine turning under the pressure of starting air it will then fire and run on fuel. As soon as the engine fires and is running on fuel the operator will then move lever 55 out of the "Ahead" "Start" position to the adjacent "Run" or "Shift" position or to any other selected intermediate position to effect operation of power means 47 to turn the maneuvering shaft 6 to the corresponding position to permit operation of the starting air valve device 35 to cut off the supply of starting air to pipe 37 and to open said pipe to atmosphere. Fluid under pressure will then be released from piston chamber 145 in the directional control device 118 by way of pipes 146 and 137, and spring 156 will move the shoe 149 out of contact with the crank shaft 2 and to the position in which pin 154 is disposed in the left-hand recess 155 in link 151.

The engine now operating in the ahead direction, the operator may adjust the speed to any desired degree, as limited by the position of the maneuvering control lever 55, by operation of lever 109 of the speed control device 108.

Whenever the operator desires to stop the engine regardless of the direction of its operation, he need only move the control lever to "Stop" position to effect operation of power means 47 to correspondingly position the maneuvering shaft 6, since movement of the maneuvering control shaft 6 to its "Stop" position will actuate cam 84 to turn the fuel control shaft 3 to the fuel cut-off position indicated by the dot and dash line 4. When the supply of fuel to the engine is thus cut off the engine will stop.

When the engine is stopped from operation in the ahead direction it may be restarted in the same direction in a manner which will be readily apparent from the above description.

Summary

It will now be seen that I have provided a control apparatus for controlling the starting, stopping, reversing and speed of a reversible engine which is relatively simple, yet positive in operation and which is particularly adapted to control such operation from a remote control station. The apparatus is also particularly adapted for controlling the maneuvering shaft of an engine which is arranged to control the starting and reversing of the engine. Fuel control means are so arranged as to positively cut off the supply of fuel to the engine upon initiating a reverse in the direction of operation of the engine but to supply fuel to the engine just as soon as the engine starts to turn in the selected direction in order to obtain as prompt operation as possible of the engine in said direction. The fuel control means is interlocked with the maneuvering shaft so that the engine may be stopped by operation of said shaft, and by suitable adjustment of said shaft the amount of fuel supplied to the engine by operation of the speed control device 108 may be limited to any chosen degree regardless of the adjustment of said device.

Having now described my invention, what I claim as new and desire to secure by Letters Patent, is:

1. An apparatus for controlling the direction of operation of a reversible engine and for also controlling the supply of fuel to said engine comprising in combination, a first control pipe, a second control pipe, operator's control means selectively operable to supply fluid under pressure to either one of said pipes and to at the same time open the other pipe to atmosphere, reversing means conditionable in response to fluid under pressure supplied to said first pipe to condition said engine for operation in one direction and conditionable in response to fluid under pressure supplied to said second pipe to condition said engine for operation in the opposite direction, starting means operable to initiate starting of said engine in either direction, fuel cut-off means operable by fluid under pressure to cut-off the supply of fuel to said engine, means operable upon release of fluid under pressure from said fuel cut-off means to effect a supply of fuel to said engine, and directional control means arranged to respond to direction of operation of said engine and comprising means operable upon starting of said engine in said one direction to close communication between said first pipe and said fuel cut-off means and to open communication between said fuel cut-off means and said second pipe and operable upon starting of said engine in said opposite direction to open the first named communication and to close the second named communication.

2. An apparatus for controlling the direction of operation of a reversible engine and for also controlling the supply of fuel to said engine comprising in combination, a first control pipe, a second control pipe, operator's control means selectively operable to supply fluid under pressure to either one of said pipes and to at the same time open the other pipe to atmosphere, reversing means conditionable in response to fluid under pressure supplied to said first pipe to condition said engine for operation in one direction and conditionable in response to fluid under pressure supplied to said second pipe to condition said engine for operation in the opposite direction, starting means operable to initiate starting of said engine in either direction, fuel cut-off means op-

erable by fluid under pressure to cut off the supply of fuel to said engine, means operable upon release of fluid under pressure from said fuel cut-off means to effect a supply of fuel to said engine, valve means adjustable to establish communication between said fuel cut-off means and either one of said first and second control pipes and at the same time to close communication between said fuel cut-off means and the other one of said control pipes, directional means responsive to direction of rotation of a rotatable part of said engine, and means arranged to control said valve means operable by said directional means upon rotation of said part in a direction contrary to the one of said pipes supplied with fluid under pressure to effect operation of said valve means to open communication between the last named pipe and said fuel cut-off means and operable upon rotation of said part in the direction determined by the one of said pipes supplied with fluid under pressure to effect operation of said valve means to open communication between said fuel cut-off means and the one of said pipes which is open to atmosphere.

3. An apparatus for controlling the direction of operation of a reversible engine and for also controlling the supply of fuel to said engine comprising in combination, a first control pipe, a second control pipe, operator's control means selectively operable to supply fluid under pressure to either one of said pipes and to at the same time open the other pipe to atmosphere, reversing means conditionable in response to fluid under pressure supplied to said first pipe to condition said engine for operation in one direction and conditionable in response to fluid under pressure supplied to said second pipe to condition said engine for operation in the opposite direction, starting means operable to initiate starting of said engine in either direction, fuel cut-off means operable by fluid under pressure to cut off the supply of fuel to said engine, means operable upon release of fluid under pressure from said fuel cut-off means to effect a supply of fuel to said engine, valve means adjustable to establish communication between said fuel cut-off means and either one of said first and second control pipes and at the same time to close communication between said fuel cut-off means and the other one of said control pipes, directional control means adapted to respond to rotation of a rotatable part of said engine to control said valve means and comprising means operable upon rotation of said part in a direction contrary to the one of said pipes supplied with fluid under pressure to effect operation of said valve means to open communication between the last named pipe and said fuel cut-off means and operable upon rotation of said part in the direction determined by the one of said pipes supplied with fluid under pressure to effect operation of said valve means to open communication between said fuel cut-off means and the one of said pipes which is open to atmosphere, and means controlled by said operator's control means operable to render said directional control means either responsive or non-responsive to rotation of said part.

4. An apparatus for controlling the starting and operation of an engine in either an ahead or an astern direction and for also controlling the supply of fuel to said engine comprising in combination, an operator's control device comprising a lever having an ahead starting position and an astern starting position, two control pipes, means operable by said lever in said ahead starting

position to open one of said pipes to atmosphere and to supply fluid under pressure to the other pipe, and operable by said lever in said astern position to open said other pipe to atmosphere and to supply fluid under pressure to said one pipe, fuel control means having a fuel cut-off position and being movable out of said position to supply fuel to said engine, actuating means operable by fluid under pressure to move said fuel control means to said fuel cut-off position, means operable upon release of fluid under pressure from said actuating means to move said fuel control means out of said fuel cut-off position, directional means responsive to direction of operation of said engine, one valve arranged to open and close communication between said actuating means and said one pipe, a second valve arranged to open and close communication between said actuating means and said other pipe, means operable by said directional means upon operation of said engine in said ahead direction to effect movement of said one valve to its communication opening position and of said second valve to its communication closing position and operable by said directional control means upon operation of said engine in said astern direction to effect movement of said one valve to its communication closing position and of said second valve to its communication opening position.

5. An apparatus for controlling the starting and reversing of a reversible engine and for also controlling the fuel supply to said engine comprising in combination, an engine maneuvering shaft having ahead and astern starting positions and also having a stop position, reversing means conditionable in response to movement of said shaft to said ahead starting position to condition said engine for operation in an ahead direction and conditionable in response to movement of said shaft to said astern position to condition said engine for operation in an astern direction starting means operable by said shaft in said ahead and astern starting positions to initiate starting of said engine, fuel control means having a fuel cut-off position and operable therein to cut off supply of fuel to said engine and being movable out of said cut-off position to supply fuel to said engine, directional control means controlled by a rotatable part of said engine and comprising means operable upon rotation of said part in a direction contrary to the starting position of said shaft to effect movement of said fuel control means to said cut-off position and operable upon rotation of said part in the direction determined by the starting position of said shaft to permit movement of said fuel control means out of said cut-off position, and means operable by said shaft upon movement to said stop position to also effect operation of said fuel control means to its fuel cut-off position.

6. An apparatus for controlling the starting of an engine and the supply of fuel to said engine comprising in combination, starting means for said engine, operator's control means adjustable to effect operation of said starting means, fuel control means for said engine having a fuel cut-off position and adjustable out of said position to vary the amount of fuel supply to said engine, a separate operator's control device operable to effect adjustment of said fuel control means out of said fuel cut-off position, limiting means adjustable to limit adjustment of said fuel control means out of said cut-off position to any chosen maximum degree, and means operable by said

operator's control means to adjust said limiting means.

7. An apparatus for controlling the starting of an engine and the supply of fuel to said engine comprising in combination, starting means for said engine, operator's control means comprising a lever having an engine start position and a fuel limiting zone, means operable by said lever in said start position to effect operation of said starting means, fuel control means for said engine having a fuel cut-off position and being operable upon movement out of said position to supply fuel to said engine in an amount proportional to the extent of such movement, speed regulating means operable to adjust said fuel control means out of its fuel cut-off position, a separate operator's control device operable to control said speed regulating means, and means adjustable by said lever upon adjustment in said fuel limiting zone to limit to any chosen degree the extent of adjustment of said fuel control means out of its fuel cut-off position by said speed regulating means.

8. An apparatus for regulating the supply of fuel to an engine comprising in combination, fuel control means for said engine having a fuel cut-off position and a fuel control zone at one side of said position for supplying fuel to the engine in an amount proportional to the extent of movement of said means out of said cut-off position, an operator's speed control device operable to adjust said fuel control means in said zone, limiting means adjustable to limit to any desired degree the extent of movement of said fuel control means out of said cut-off position, and a separate engine starting device operable to adjust said limiting means.

9. An apparatus for regulating the supply of fuel to an engine comprising in combination, fuel control means for said engine having a fuel cut-off position and a fuel control zone at one side of said position for supplying fuel to the engine in an amount proportional to the extent of movement of said means out of said cut-off position, an adjustable speed governor operable by said engine, an operator's speed control device operable to adjust said speed governor, means operable by said speed governor to adjust said fuel control means out of said fuel control position in said zone to a position depending upon the adjustment of said speed control device, limiting means adjustable to limit to any desired degree movement of said fuel control means out of said fuel cut-off position into said zone by operation of said governor, an operator's engine starting control device, and means operable by said engine starting control device to adjust said limiting means.

10. An apparatus for regulating the supply of fuel to an engine comprising in combination, fuel control means for said engine having a fuel cut-off position and a fuel control zone at one side of said position for supplying fuel to the engine in an amount proportional to the extent of movement of said means out of said cut-off position, an adjustable speed governor operable by said engine, an operator's speed control device operable to adjust said speed governor, means operable by said speed governor to adjust said fuel control means out of said fuel control position in said zone to a position depending upon the adjustment of said speed control device, limiting means adjustable to limit to any desired degree movement of said fuel control means out of said fuel cut-off position into said zone by operation of said governor, and also operable to move said

fuel control means to said fuel cut-off position, and separate operator's control means operable to adjust said limiting means.

11. An apparatus for controlling the reversing and starting of a reversible engine and for also controlling the supply of fuel to said engine comprising in combination, reversing means for said engine, starting means for said engine, an operator's control device comprising a lever having ahead and astern start positions and means operable upon movement of said lever to said positions to effect operation of said reversing means to condition said engine for operation and to start said engine in respectively ahead and astern directions, fuel control means for said engine having a fuel cut-off position and a fuel supply zone adjacent said cut-off position, operator's control means comprising a lever having an engine idling position and means operable by said lever upon movement out of said idling position to adjust said fuel control means away from said fuel cut-off position into said zone, limiting means adjustable to limit to any desired degree movement of said fuel control means away from said cut-off position and also adjustable to move said fuel control means to said cut-off position, and means operable by said operator's control device to adjust said limiting means.

12. An apparatus for controlling the reversing and starting of a reversible engine and for also controlling the supply of fuel to said engine comprising in combination, an engine maneuvering shaft, operator's control means comprising a lever having ahead and astern start positions and a stop position and means operable upon movement of said lever to its different positions to effect movement of said shaft to corresponding positions, engine reversing means controlled by said shaft and operable upon movement of said shaft to either its ahead or astern position to condition said engine for operation in respectively either an ahead or astern direction, starting means operable by said shaft in said ahead and astern positions to effect starting of said engine, fuel control means for said engine having a fuel cut-off position and being adjustable out of said position to supply fuel to said engine, an operator's speed control device operable to effect adjustment of said fuel control means out of said cut-off position, limiting means adjustable to limit to any desired degree adjustment of said fuel control means out of said cut-off position by operation of said speed control device and also adjustable to move said fuel control means to said cut-off position, and means operable by said shaft to adjust said limiting means.

13. An apparatus for controlling the reversing and starting of a reversible engine and for also controlling the supply of fuel to said engine comprising in combination, an engine maneuvering shaft, operator's control means comprising a lever having ahead and astern start positions and a stop position and means operable upon movement of said lever to its different positions to effect movement of said shaft to corresponding positions, engine reversing means controlled by said shaft and operable upon movement of said shaft to either its ahead or astern position to condition said engine for operation in respectively either an ahead or astern direction, starting means operable by said shaft in said ahead and astern positions to effect starting of said engine, fuel control means for said engine having a fuel cut-off position and being adjustable out of said position to supply fuel to said engine, an operator's speed control device operable to effect adjustment of said fuel control means out of said cut-off position, limiting means adjustable to limit to any desired degree adjustment of said fuel control means out of said cut-off position by operation of said speed control device and also adjustable to move said fuel control means to said cut-off position, means operable by said lever to adjust said limiting means, fuel cut-off means operable to move said fuel control means to said cut-off position, directional control means controlled by direction of operation of said engine, and mechanism controlled by said directional control means and cooperative with said operator's control device to effect operation of said fuel cut-off means upon movement of said lever to either said ahead or astern position with said engine operating in respectively either the astern or ahead direction, said directional control means being operable upon operation of said engine in the direction corresponding to the position of said lever to render said fuel cut-off means ineffective, and means operable upon rendering said fuel cut-off means ineffective to render said fuel control means adjustable by said operator's speed control device.
